STAIRS

John W. Thornton, San Francisco, and Peter D. Donlon, Piedmont, Calif., assignors to Prefab Stairs and Tile, Inc., a corporation of California

Application August 7, 1945, Serial No. 609,400

2 Claims. (Cl. 72—96)

1

This invention relates to improvements in the manufacture of stairs and particularly to a method which can be successfully utilized to provide a flight of stairs fabricated of separate units and made of concrete.

In dwellings and the like, straight rises of stairs are provided by cutting two or more stringers from heavy timbers, notching these to provide the outline of the stair treads and risers and placing these in position. Subsequently, risers and treads are secured in place. If such stairs are exposed to weather, their life is relatively short and it is necessary to repair them at frequent intervals, for the stringers and the support members provided beneath the stringers rot away in a relatively few years. In accordance with the present invention, we have provided a successful method enabling stairs to be cast from concrete and faced as with tile or the like to provide a complete and a waterproof structure. The use of tile, bricks and the like for stairs is not, of course, new. However, these have heretofore only been employed in conjunction with wood supports, the usual practice being to build a wooden ramp and then to build the stairs up on this ramp. However, the weight of the tile or brick presents a heavy load upon the wooden supports and, because the structure provided is not waterproof and cannot be made such, the life of the ramp is relatively short, particularly as compared to that of the tile.

In accordance with our invention, we precast a suitable stair form including the riser and tread facings.

When a turn is required in the stairs, some form of support is usually improvised. Usually the final structure is a complicated maze of stringers and supports restricting the head room beneath the stairs. We have provided a novel stair structure in which precast concrete stringers, risers and treads are utilized. The stringers are supported from the side walls and intermediate support columns are not required. This is of great advantage for it ensures a maximum of head room under the stairs and at the same time shortening installation time and reducing the cost.

Another object of this invention is to provide a novel stair winder construction.

An additional object of the invention is to provide a stair construction in which precast units are employed and are supported from the walls alone.

Further, it is an additional object of the present invention to provide a method of manufacture for a combination precast concrete stair in conjunction with a riser set of tiles and a tread set of tiles or like facing material.

Another object of the present invention is to provide a novel precast concrete stair structure.

Referring to the drawing accompanying and forming a part hereof, Figure 1 is a section through a suitable mold structure illustrating a

2

mold and construction of the novel precast concrete stair structure of the present invention.

Figure 2 is a plan view of the mold structure illustrated in use in Figure 1.

Figure 3 is a section illustrating the precast stairs supported on a straight riser.

Figure 4 is a plan view of a stringer installation.

Figure 5 is a view taken along the line 5—5 of Figure 4.

Figures 6 and 7 are respectively views taken along the lines 6—6 and 7—7 of Figure 4, illustrating only the inside riser-stringer about which the stair turn is made.

Figure 8 is a view, similar to Figure 4, of the completed stairs.

Referring to the drawing accompanying and forming a part hereof, we first provide a suitable mold including side walls 7 and 8 and end walls 9 and 11. Side walls 7 and 8 are spaced apart a distance sufficient to provide a step of the desired tread width, wall 7 being shorter than wall 8 to provide a fall of about $\frac{1}{4}$ " in each foot of tread width. The distance between the inter-

edges of strips 9 and 11 corresponds to the width of the individual stair desired. A bottom 12 is secured in position and over a portion of this extends a cooperative arcuate mold member 14 secured by nails 16 to one or more transverse supports 11. Along the inner face of strip 7 is mounted a short strip 18, the latter being positioned directly upon bottom 12 to support the riser facing above the end of the riser. Member 14 is used to define the inside face of each stair; its ends 20 and 25 each slope respectively toward the upper or outer edge of the mold so that, as will appear, mortar can be placed between each stair and a supporting stringer.

To lend strength to the final structure, suitable reinforcing elements such as structural steel reinforcing bars 19 are preferably positioned in the mold before the concrete is poured. One or more riser tiles, depending upon the depth of the mold, such as that indicated at 21, are positioned on strip 18. After this, a suitable concrete mixture

is poured in the mold and is trowelled off level with edges 7, 8, 9 and 11. As the concrete cures, tread tiles indicated by numeral 22 are positioned directly upon the concrete. If desired, a sheet metal flashing plate 23 is positioned over each mold end wall 9 and 11 and beneath the edge of each border tread tile. The flashing is secured to the adjacent wall structure which confines the sides of the stair (Figure 3) to complete the

waterproofness of the structure and prevent water from leaking down alongside of each of the stairs.

While the precast stairs described can be utilized on the ordinary and usual wood stringers, we prefer to employ these stairs in conjunction with the novel, precast concrete stringers which also form a part of our invention.

Referring particularly to Figures 4 and 5, we

wish to point out that utilization of precast, concrete stringers enables a simplified support structure to be utilized. Thus, as appears in Figures 4 and 5, it is only necessary to build a confining wall such as we have indicated generally at 41 and comprising sheathing 42 supported upon suitable studding or columns 43. The construction of the wall can be in any desired fashion usual in the art and as dictated by the needs and the details of the building under construction. In the construction illustrated in Figures 4 and 5, the stairway rises from the right-hand portion of Figure 4, making a full 180° turn, the rise continuing on the left-hand portion of Figure 4, the stairway being confined by walls 61, 62 and 63. To provide this, opposite stringer pairs 46 and 47 are mounted on the opposite walls, stringer 47 being suitably supported by a plurality of clips 45 nailed to wall 61 while stringer 46 is secured by like clips to a central column 48 about which the stair turn is made. The central column can be one member or can be fabricated of several; in any case, it is quite small and the turn about it is a tight one, requiring only a very small area as compared to that usually required. In reality, on a 180° turn column 48 is nothing more than a wall of minimum thickness, separating one stair run from another. Stringer 47 is continued by stringers 49 and 50 secured to wall 62 on which they are also positioned by clips 45. Stringers 49 and 50 are preferably separate so that portion 51 of stringer 50 can overlap and extend along portion 52 of stringer 49. In this way, minor adjustments in length to suit the length of the wall can be made.

The stair rise along the third wall 63 is provided by stringers 53, an oppositely positioned stringer 54 on column 48 continuing the upward run of the stairs. The 180° turn about column 48 is effected by the novel stringer structure illustrated particularly in Figures 6 and 7 and indicated by numeral 71. This includes a first portion 72 continuing the rise of stringer 46 along face 73 of column 48. A second portion 74 of the stringer rests against face 76 of column 48, portion 74 being at 90° to portion 72 and including a plurality of angularly positioned seating surfaces 77, 78 and 79 thereon to support the inner edge of the several wedge-shaped stairs required to fit the turn and resting on support faces 81, 82 and 83 on stringer 47 and stringer 49. A third portion 62A of stringer 71 fits against face 63A on column 48, this portion including seating surfaces 84, 85 and 86 for the remainder of the steps on the turn. Beyond the turn, stringer 54 and stringer 53 provide for mounting of the further stairs and risers.

The construction illustrated is designed for a 180° turn, from stair 107 to stair 108, and made with six stairs 101-106, as appears in Figure 8. Those skilled in the art can readily adapt the structure to a turn of different extent and to accommodate a different number of rises in the turn. The stairs utilized on the turn are basically like those shown in construction in Figures 1-3, except that the molds are made of a suitable angularity to fit the angle of the tread. The stringer 71 is preferably precast in one piece, suitable reinforcing being provided in the structure.

To facilitate assembly and securing of the precast steps in place, the forward corner of each riser and stair is relieved as at 91. This permits

mortar 92 to be inserted between the stair, the riser, and the stringer as appears in Figure 3. In addition, the upward slope on the inner face of the tread portion and the outward slope on rear face of the riser permits mortar to be inserted between these and the stringer as at 96 and 97. Mortar is also placed between the foot of the riser and the adjacent portion of the lower stair tread, as at 94.

With the stairs extended between risers secured only on the opposite sides of the confining walls, a maximum of head room is available. In some building designs this has enabled the overall height of the building to be reduced as compared to that necessary when usual wood construction is employed.

We claim:

1. A stair construction comprising a first and a second side wall in a spaced parallel vertical relationship; an end wall joining said side walls and at substantially 90° to each of said side walls; an intermediate vertical column positioned substantially midway between and substantially parallel to said side walls and in a spaced relation to said end wall to provide a U-shaped stair well; said intermediate column having a first column wall parallel to said first side wall, a second column wall parallel to said second side wall, and an end column wall parallel to said first mentioned end wall and joining said first and second column walls; a first stair stringer extending upwardly and secured along said first side wall; a second stair stringer secured to said end wall and continuing said first stringer upwardly; a third stair stringer secured to said second side wall and continuing said second stringer upwardly; a stringer secured to said vertical column and consisting of a first portion extending upwardly along the first column wall, a second portion extending along the end column wall and continuing said first portion upwardly, and a third portion extending along the second column wall and continuing the second portion upwardly, each stringer being provided with spaced horizontal tread supports, the tread supports of the stringers on the side walls and said first mentioned end wall being in the same planes as the corresponding tread supports of the column stringer, and stair treads extending between corresponding stair tread supports.

2. A stair construction, as in claim 1, wherein the column stringer consists of pre-cast concrete.
